UNITED STATES PATENT OFFICE.

JOHN JOFFE, OF LONDON, ENGLAND.

GRAMOPHONE AND LIKE SOUND-REPRODUCING INSTRUMENT.

1,427,211.

Specification of Letters Patent. Patented Aug. 29, 1922.

Application filed January 5, 1922. Serial No. 527,262.

To all whom it may concern:

Be it known that I, JOHN JOFFE, a subject of the King of Great Britain, and resident of London, England, have invented 5 certain new and useful Improvements in or Relating to Gramophones and like Sound-Reproducing Instruments (for which I have filed application for patent in Great Britain, Serial No. 23,032, dated August 4, 1920), 10 of which the following is a specification.

This invention relates to gramophones and like sound reproducing instruments, and has for its object the provision of a sound reproducing instrument having an 15 efficient controlling apparatus of simple construction.

The invention further relates to multiple record machines provided with means preferably coin-controlled whereby any selected 20 one of the records can be brought into use as desired.

The invention consists broadly of a gramophone or like sound reproducing instrument having a stylus supported above the 25 record on a counter-weighted pivoted tone arm, wherein the stylus is lifted from the record by means of the counter-weight and is lowered into operative engagement with the record by means of a movable weight 30 adapted to move into operative position by gravity, after it has been set in motion by mechanism under the control of the operator, and to be arrested in such position by means of mechanism automatically released 35 when the stylus arrives at the end of the record, so that the weight will move automatically out of operation.

The weight is preferably in the form of a ball adapted to roll down a pivoted inclined operating chute or guide-way fixed 40 on the pivoted tone arm or operatively connected thereto by link and lever mechanism.

This guide-way is arranged in such a manner that the ball will roll down from 45 its delivery to its discharging end, and is provided with a releasable stop arranged to arrest the ball at a position where its weight will depress the chute sufficiently to lower the stylus into operative engagement with 50 the record.

In applying the invention to multiple record apparatus a series of gramophones may be arranged one above the other, and each provided with an operating chute adapted 55 to receive a ball from a casing containing a vertical column of them and provided

with means for delivering them one at a time on to the operating chute or guide way. Mechanism is also provided for bringing the operating chute of any selected gramophone into ball receiving position in the ball casing. Coin freed mechanism may be provided for delivering the balls on to the pre-selected operating chute.

Various embodiments of the invention are 65 illustrated diagrammatically by the accompanying drawings, wherein Figure 1 is a perspective view of a portion of a form of the apparatus wherein the operative portion of the ball guide way is fixed on the tone 70 arm. This view also shows coin-controlled ball delivery mechanism. Figures 1^a and 1^b illustrate a releasable ball stop, Figure 1^c, a detail of the record brake mechanism and Figure 1^d a plan of the record selecting 75 mechanism.

Figure 2 is a sectional view of a modified form of the apparatus designed for multiple records, the ball guide way being pivoted above the tone arms and connected thereto 80 by link and lever mechanism. Figures 3, 4 and 5 are views of details of the apparatus shown in Figure 2. Figures 6 and 7 are plans of the selecting and record mechanism respectively and Figure 8 a further 85 modification of the apparatus.

In these drawings 1 is the pivoted tone arm, 2 the horizontal pivot thereof, 3 the stylus or needle, and 4—4, the sound records.

The operating weights are in the form of 90 balls 6—6. These balls are delivered on the upper end of an inclined pivoted guide way which is indicated at 7 in Fig. 1, and at 7^a in Figs. 2 and 3, is pivoted on the shaft 8 in Figures 2 and 3. 9 is the removable ball- 95 arresting stop.

In the embodiment of the invention illustrated in Figure 1, the stylus 3 is mounted on a sound box 10 secured to a tone arm 1 in the usual manner and held normally out of 100 contact with the record by means of a counter weight 11 adjustably mounted on a rod 12 secured to the tone arm 1. The balls 6 are adapted to roll down a guide way 7 fixed on the tone arm 1. This guide-way is 105 of zig-zag formation as shown and a releasable stop 9 is arranged to hold the ball at a bend in the guide way 7 in a position where its weight will overcome that of the counter weight and lower the stylus 3 on to 110 a record. The releasable stop 9 is pivoted to the tone arm 1 at 220 Figures 1^a and 1^b,

and is provided with a spring 221 arranged to hold the ball retaining point of the stop 9 in the path of the ball in the operating chute or guide way 7.

- 5 A portion of the releasable stop 9 extends beyond its pivot 220 and is adapted when the tone arm has moved across the record to come into contact with a fixed adjustable rod 222 arranged to lift the stop and allow 10 the ball to run down the guide way and off its discharge end 13, and so allow the counter weight 11 to lift the stylus from the record to its normal position. Any other suitable pivoted or sliding mechanism may 15 be provided for effecting this movement of the stop 9.

The ball discharged from the end 13 of the guide way 7 is delivered on to a pivoted guide way 14 provided with a counter weight 20 15 arranged to hold the guide way normally in its uppermost position. This guide way 14 is pivoted at 16 and connected by an arm 17 and flexible connecting member 18 to a pin 19 secured to the tone arm 1. The arm 25 17 and flexible member 18 are so arranged that the weight of a ball on the guide way 14 will turn it about its pivot and pull the tone arm about its vertical pivot 20 so as to move the tone arm across the record to starting point, the ball then rolls off the guide way 14 into chutes 230 which deliver it into a ball casing 121 down which it drops and then passes on to a pivoted plunger 120 arranged in the lower end of the tubular casing 20 25 30 35 40 45 50 55 60 65 70 75 80 85 90 95 100 105 110 115 120 125 130 135 140 145 150 155 160 165 170 175 180 185 190 195 200 205 210 215 220 pull the flexible member 47 and so lift the stylus from the record into its normal position.

The ball guide-way 7^a which is provided with an adjustable balance weight 119 is not secured to a tone arm as in the previous example, but pivoted on a shaft 8, and motion is communicated to the rod 44 to lift the same and thereby lower the stylus on to the record, by the guide-way 7^a while it is being lowered by the weight of a ball delivered thereon and arrested by the releasable stop 9^a. In order to effect the upward movement of the rod 44 it is jointed to the end of a lever 51, the other end of the lever being loosely pivoted on the shaft 8. This lever is arranged to be lifted by a projection 52 arranged on a sliding lever frame 53 pivoted on the shaft 8. The projection 52 is formed on the back member of the lever frame 53, while the front member thereof consists of a rod 54 which extends under the pivoted guide-way 7^a. It will thus be seen that the guide-way 7^a when moved downwards by the weight of a ball engages and presses downwards the rod 54 which in its turn by tilting the pivot frame 53 raises the projection 52 and the lever 51 resting thereon and so the rod 44 is lifted and the stylus lowered on to a record.

When the tone arm has moved the stylus across the record it operates by a rod 55 extending therefrom a cranked shaft 56 Figures 3 and 7, which by means of a cranked member 57 Figures 3 and 4 arranged at its end causes the ball arresting stop 9^a to drop out of the path of the ball and allows the ball to run down to a releasable stop 106 Figures 2 and 6 in the guide-way 58 leading to the lower end of the ball column casing 21^a. The tone arm which in playing the record is moved against the tension of a spring 200 is returned to starting position by said spring 200 when it is raised from the record by the weight 11^a. It will be understood from the above that the raising of the tone arm from the record is effected after the ball stop 9^a has been moved out of operation by the action of the tone arm rod 55 on the cranked shaft 56 which moves the arm 57 away from the pin 240 Figure 4, extending from the stop carrying plate 241 which is secured to the pivoted lever 86. It will also be understood that the chute 7^a will be carried down by a ball until it is arrested by the pivoted stop plate 241, and that when the stop 9^a is withdrawn the ball passes through an opening in the side of the chute through an opening in a guide plate 242 Figure 3 into the vertical tube 243 down which it drops on to the stop 80 in the chute 58.

On the shaft 8 and between the two arms of the sliding lever frame 53 are pivoted a number of levers 51 as shown in Figures 2

and 6, one for the lowering rod 44 of each record, one only of these levers 51 being shown in Figure 3 for clearness; and the sliding frame is adapted to be moved along the shaft to bring the projection 52 under the lever 51 corresponding to the selected record. The mechanism for sliding the frame consists of a lever 59 pivoted at 60 and fork-shaped at its free end to engage one of the arms of the frame 53. The lever 59 is moved about its pivot by a rod 61 linked at one end to the lever and at the other to one end of an arm 62, the other end of the arm 62 being connected to a shaft 63. This shaft is rotated in its bearings the 70 desired amount by means of a quadrant 64 secured thereon and adapted to be operated by a friction roller 65 mounted on the end of a shaft 66 adapted to be rotated by hand by means of a knob 67 secured on a portion 80 of the shaft 66 extending through the casing 68 of the apparatus. On the shaft 63 is also mounted a pointer arm 69 adapted to move over a scale indicated by numerals at 85 70. It will be readily understood that by 90 rotating the knob 67 until the pointer arm 69 is opposite the number selected, the friction roller 65 will move the sliding frame 53 into the position to operate the stylus lowering mechanism of the selected record. 95 The friction roller 65 is held in operative contact with the quadrant 64 by means of a spring 71.

In order to hold the quadrant 64 in the selected position it is provided on its under 100 side with a series of projections 72, between which the end of a retaining lever 73 is adapted to be moved by an arm 81 extending from the shaft 74 and connected by a flexible connection 82, see Fig. 2, to a pivoted 105 lever 83 of which the end extends into the upper portion of the ball guide-way so that it will be operated before the ball is arrested by the stop 9^a. The operation of the lever 83 also by means of an arm 84 connected 110 thereto, rod 85, and arm 86 connected to the pivot shaft 87 of the stop 9, moves this stop into ball retaining position. The lever 73 Fig. 3, is mounted on the shaft 74 on which is also fixed an arm 75 carrying at its 115 outer end a retaining pin 76. This pin rests in a notch in the top of an arm 77 provided with a spring 150 and secured to a shaft 78 on which is also secured an arm 79 the outer end of which is provided with a return bend 120 or projection 80 extending into the path of the ball. By this arrangement when the retaining lever 73 is moved between the projection 72 on the quadrant 64 the retaining pin 76 moves into and is held by the notch 125 at the end of the arm 77, and after the tone arm by moving across to the end of the record has released the ball stop 9 the ball falls on to the projection 80 and tilts the lever 79 and thereby moves the arm 77 130

against the action of its spring 150 and away from the retaining pin 76 and so allows of the removal of the quadrant retaining lever 73 from between the projection 5 72 thereby placing the quadrant in a position ready to be operated in the selection of another record.

In order to provide means for repeating a record, an automatic releasable shutter 90 10 Figure 5 is provided to arrest a selected number of balls according to the desired number of repetitions, fed into the ball guide-way. This shutter holds the remaining number of the selected balls in the fixed 15 portion 129 of the guide-way after the first of them has passed under the shutter 90 which is arranged on the pivoted portion 7 of the chute in such a manner that when a ball runs down towards the pivoted portion 20 of the guide-way 7 the shutter closes over it by the ball pressing against a bell crank extension 91, of the shutter and thereby prevents the next of the selected balls following. The shutter 90 is provided with an arm 92 which is held by a 25 pawl 93 to keep the shutter in the closed position. After the ball is released by the stop 9 the pivoted chute 7 returns to its normal position and engages a fixed stop 30 arranged to release the pawl 93 and allow the shutter to open to receive the next of the selected balls.

The lever mechanism 83 Fig. 2, operated by the ball when forced by the plunger 120 35 from the tube 21 into the chute 129 before passing down the upper portion of the chute is also adapted by means of lever and link mechanism 94, 95 to release a brake 96 adapted to prevent rotation of the record by 40 the motor.

The apparatus is preferably provided with adjustable stop mechanism indicated at 97 45 Figures 2 and 7 for limiting the movement of the tone arms when returning to starting position.

The balls are preferably transferred from the lower end of the chute to its upper end by a vertical tube 21 up which they are forced by any suitable means, such as a 50 plunger 120 and they may be released for operation in the chute by any suitable coin freed or other mechanism such for example as described with reference to Fig. 1.

In operating the apparatus illustrated in 55 Figure 2, the knob 67 is rotated to bring the pointer arm 69 into the position corresponding to the selected record as described above, and after the insertion of a coin in the chute 100 the handle 101 is rotated, this handle is 60 secured on the end of a shaft 102 on the end of which is fixed a crank 103, this crank operates a link 104 which is attached to the end of a pivoted lever 105. The lever 105 lifts the plunger 120 and thereby forces the last 65 ball discharged from the guide-way 58 into

the ball casing 21 upwards and thereby delivers the uppermost ball from the top of the casing into the upper portion 7 of the guide-way.

In order to prevent the ball rolling down 70 the chute 58 into the casing 21 before a coin has been inserted in the chute 100 a pivoted ball retaining stop 106 Figures 2 and 6, is provided. This stop is moved into retaining position by a projection 111 on the lever 107 75 when the said projection is engaged by the lever 81 during the movement of this lever as described above.

The stop 106 is arranged to be moved out of the path of the ball by means of a bell 80 crank or like lever 107, 108, of which the arm 108 is linked at its end to a pivoted lever 109 having an end portion extending into the coin chute in such a manner that the weight of the coin operates to liberate 85 the ball held by the catch 106 and so allows it to run down into the casing 21 on the top of the plunger 120. The column of balls are held in the casing 21 by means of a by-pass 29 as described with reference to Figure 1. 90

The coin-chute 100 is preferably provided with an obturator 110 adapted to be moved into the coin-chute during the operation of the lever 81 described above, so that should a second coin be inserted before the apparatus has completed its response to the first one, the second coin will be arrested until the operation due to the first coin is completed.

In the modification of the apparatus illustrated by Figure 8 an electro-magnet 210 is used for lowering the needle on to the record. This electro-magnet is arranged under the lever 211 pivoted on the shaft 8 and adapted to engage the rod 54 and by lowering the 105 same raise the projection 52 of the lever frame 53 and thereby raise the lever 51 under which the projection 52 has been drawn by the selecting mechanism operated by the knob 67. The raising of the lever 51 110 lifts the weight 11 and rod 44 which by tilting the lever 45 about its pivot 46 allows the pivoted portion 1 of the tone arm connected to the lever by the flexible cord 47 to lower the stylus 3 into contact with the record 4. 115 Any suitable source of electric power 212 is placed in the circuit 213 of the electro magnet 210, the said circuit being divided by contacts 214 and 215, the latter being a fixed contact and the former a movable one fixed on a lever 216 pivoted at 217 and provided at one end with an adjustable balance weight 218 and at the other with a trough adapted to receive a coin 219 to which it has been delivered by means of the coin chute 100. The coin 219 delivered into the trough of the lever 216 lowers the same by its weight and then rolls down into contact with the stop 9 at the same time bringing the contacts 214 and 215 into engagement and thereby ener- 130

gizing the electro-magnet 210 which operates the mechanism to lower the stylus on to the record as described above. When the stylus arrives at the end of the records the arm 55 carried by the tone arm 41 moves into engagement with the cranked rod 56 and so moves the stop 9 out of the path of the coin 219 which then drops through the chute 220 into a coin till or receptacle. The trough 10 end of lever 216 being freed from the weight of the coin is raised by the counter weight 218 and so separates the contacts 214 and 215 thereby de-energizing the magnet 210, this enables the counter weight 119 to raise 15 the lever 211 and consequently the weight 11 to raise the stylus 3 from the record 4.

The selecting mechanism is similar to that described above, the catch mechanism for the arm 75 being dispensed with and the said arm connected by a rod or flexible extension 221 to an extension of the lever 211 so that when this lever is down it raises the end of the arm 78 between the projection 72 of the selecting quadrant 64 and so holds 25 the same in position until the magnet 210 is de-energized as described above. The arm 81 on the pivoted rod 74 is connected by a rod or flexible extension 223 to the lever 95 of the brake 96 so that the record stopping 30 brake will be removed from the record 4 immediately after the energizing of the magnet 210 by the weight of a coin in the trough of the lever 216.

What I claim and desire to secure by Letters Patent is:—

1. A sound reproducing instrument having a sound box and a stylus supported above the record on a counter-weighted pivoted tone arm, wherein the stylus is lifted from the record by means of the counter weight, and means are provided for lowering the stylus into operative engagement with the record after the record has been set in motion by mechanism under the control of the operator, means being also provided for automatically stopping the record when the sound box arrives at a predetermined position and for raising the stylus therefrom.

2. A sound reproducing instrument having means for lowering the stylus on to its records comprising a ball adapted to roll down a pivoted inclined guide-way fixed on the pivoted tone arm, the guide-way being arranged in such a manner that the ball can roll down it from the delivery to the discharging end, and provided with a stop arranged to arrest the ball at a position where its weight will lower the stylus into operative engagement with the record, mechanism being provided for releasing the stop when the sound box arrives at a predetermined position.

3. A sound reproducing instrument comprising a number of gramophones each hav-

ing a record mounted on a common motor driven shaft, means for holding the stylus normally out of contact with the record, a brake normally in engagement with the record driving shaft, means for selecting 70 any particular record and releasing the brake and means for lowering the stylus on to the record, comprising a ball and a pivoted inclined guide-way down which it is adapted to roll, the pivoted guide way being connected to the tone arm by link and lever mechanism, the guide-way being provided with a stop arranged to arrest the ball at a position where its weight will 75 lower the stylus into operative engagement 80 with the record, and mechanism for releasing the stop when the sound box arrives at a predetermined position, and means for raising the stylus from the record at the end of the sound reproduction.

4. A sound reproducing instrument comprising a number of gramophones each having a record mounted on a common motor driven shaft, means for holding the stylus normally out of contact with the record, a 90 brake normally in engagement with the record driving shaft, means for selecting any particular record and releasing the brake, and means for lowering the stylus on to the record comprising a ball adapted 95 to roll down an inclined pivoted guideway divided into two portions inclined to each other in plan and means for removing the stylus from the record at the end of the sound reproduction.

5. A sound reproducing instrument having means for lowering the stylus on to the records, comprising a ball adapted to roll down an inclined pivoted guide-way divided into two portions inclined to each other in 105 plan, the releasable ball stop being arranged in a curved portion of the guide-way connecting the two portions thereof.

6. A sound reproducing instrument comprising a number of gramophones each having a record mounted on a common motor driven shaft, means for holding the stylus normally out of contact with the record, a brake normally in engagement with the record driving shaft, means for selecting 110 any particular record and releasing the brake, and a movable weight and means for bringing said weight into position to lower the stylus of the selected record into contact with the record and for removing the weight 120 when the sound box reaches a predetermined position.

7. A sound reproducing instrument having a stylus supported above the record on a counter-weighted pivoted tone arm, 125 wherein the stylus is lifted from the record by means of the counter-weight, the instrument being also provided with a movable weight and with means for bringing said weight into position to lower the stylus 130

of the selected record into operative engagement with the record after the record has been set in motion by mechanism under the control of the operator, means being 5 also provided for automatically stopping the record when the sound box arrives at a predetermined position and for removing the weight from stylus-lowering position.

8. A multiple unit gramophone provided 10 with means for feeding one of a series of balls on to anyone of a series of chutes mounted on a vertical shaft at different angles and each provided with an extension adapted to be moved in a horizontal slot in 15 a tubular casing down which a ball is delivered by hand operated coin controlled mechanism, each chute being adapted to deliver a ball to a particular gramophone, the said vertical shaft being provided with 20 means for rotating it from the outside of the apparatus so that it can be moved into the position necessary to bring a selected record into operation.

9. A sound reproducing instrument comprising a number of gramophones each having 25 a disc record mounted one above the other on a vertical motor driven shaft each tone arm being divided into two portions one carrying the sound box and stylus and 30 pivoted horizontally to the other portion which is vertically pivoted at its end over an opening leading to a common sound conduit provided at its extremity with a sound horn means for holding the stylus normally 35 out of contact with the record, a brake nor-

mally in engagement with the record driving shaft, means for selecting any particular record and releasing the brake and means for lowering the stylus of the selected record into contact with the record and for removing it therefrom when the sound box reaches a predetermined position: 40

10. A sound reproducing instrument comprising a number of gramophones each having 45 a record mounted on a common motor driven shaft, means for holding the stylus normally out of contact with the record, a brake normally in engagement with the record driving shaft, means for selecting any particular record and releasing the 50 brake and means for lowering the stylus on to the record comprising a ball and a pivoted inclined guide-way down which it is adapted to roll, the pivoted guide-way being connected to the tone arm by link and 55 lever mechanism, the guide-way being provided with a stop arranged to arrest the ball at a position where its weight will lower the stylus into operative engagement with the record, and mechanism for releasing the 60 stop when the stylus arrives at the end of the record, and means for raising the stylus from the record at the end of the sound reproduction each tone arm being provided with a projection adapted to operate the 65 ball releasing mechanism when the sound box reaches a predetermined position.

In witness whereof I affix my signature.

JOHN JOFEH.
